CLAIM

The ornamental design for a set of playing cards, as shown and described.

DESCRIPTION

The file of this patent or patent application contains at least one drawing/photograph executed in color. Copies of this patent or patent application with color drawing(s)/photograph(s) will be provided by the Office upon request and payment of the necessary fee.

FIG. 1 is a face up view of a first suit of the set of playing cards.

FIG. 2 is a face up view of a second suit of the set of playing cards.

FIG. 3 is a face up view of a third suit of the set of playing cards.

FIG. 4 is a face up view of a fourth suit of the set of playing cards.

FIG. 5 is a face up view of a fifth suit of the set of playing cards.

FIG. 6 is a face up view of a sixth suit of the set of playing cards.

FIG. 7 is a face up view of a seventh suit of the set of playing cards.

FIG. 8 is a face up view of an eighth suit of the set of playing cards.

FIG. 9 is a face up view of a ninth suit of the set of playing cards.

FIG. 10 is a face up view of a tenth suit of the set of playing cards.

FIG. 11 is a face up view of an eleventh suit of the set of playing cards.

FIG. 12 is a face up view of a twelfth suit of the set of playing cards; and,

FIG. 13 is a face up view of a thirteenth suit of the set of playing cards.

The fifty two (52) cards shown in FIGS. 1-13, in combination, consist of a single deck of playing cards.
